UNITED STATES PATENT OFFICE.

JOHN GRAVES, OF BROOKLYN, NEW YORK, ASSIGNOR TO HIMSELF AND LOUIS MONJO, OF SAME PLACE.

DESIGN FOR A SAD-IRON HOLDER.

SPECIFICATION forming part of Design No. 24,240, dated April 23, 1895.

Application filed November 30, 1894. Serial No. 530,490. Term of patent 7 years.

To all whom it may concern:

Be it known that I, JOHN GRAVES, a citizen of the United States, and a resident of Brooklyn, county of Kings, State of New York, have invented and produced a certain new and original Design for Sad-Iron Holders, of which the following is a specification, reference being had to the accompanying drawings, in which—

- 10 Figure 1 shows a plan, and Figs. 2 and 3, sectional views thereof.

The leading feature of my design consists in a raised, flanged and corrugated surface of the sheet metal top, and in the curved legs, and 15 the lines of the flange and corrugation of the top descending with easy curves into the legs.

A is the top of the holder which is approximately triangular in shape.

B is a lengthwise and C a crosswise flange, 20 the former turning up, the latter down. The flange B at its extremities runs into and disappears in the legs D E. The flange C at its extremities runs into and disappears in the legs E E.

G G are lengthwise corrugations approximately parallel to the flange B, and at their rear extremities running into and disappearing into the legs E E.

H H are crosswise corrugations.

The front leg D has sides d d bent down 30 from the top A giving the leg an angular shape and the said sides J J descending with easy curves from the top of the flange B to the lowest point of the leg. The rear legs K K are formed by bending down the corners of the 35 top A and the flange B B runs down into the outside of the said legs with an easy curve as shown, while the flange C runs down into the inside of said legs.

What I claim is—

40 The design for a sad iron holder, as herein shown and described.

JOHN GRAVES.

In presence of—

BERNARD J. BECKE,
HENRY V. BROWN.
